(57) **CLAIM**

The ornamental design for a hockey-stick container holder as shown and described.

DESCRIPTION

FIG. 1 is a bottom, rear, left side isometric view of a hockey stick container holder;

FIG. 2 is a front elevation view of the hockey stick container holder illustrated in FIG. 1;

FIG. 3 is a rear elevation view of the hockey stick container holder illustrated in FIG. 1;

FIG. 4 is a left side elevation view of the hockey stick container holder illustrated in FIG. 1;

FIG. 5 is a right side elevation view of the hockey stick container holder illustrated in FIG. 1;

FIG. 6 is a top plan view of the hockey stick container holder illustrated in FIG. 1;

FIG. 7 is a bottom plan view of the hockey stick container holder illustrated in FIG. 1; and,

FIG. 8 is an environmental view of the hockey stick container holder illustrated in FIG. 1.

The dash-dot-dash broken lines consisting of unevenly sized dashes define the bounds of the claimed design and form no part of the claimed design. The even-length dotted broken lines show portions of the hockey stick container and environment and form no part of the claimed design.

1 Claim, 8 Drawing Sheets
